J. DICKIE.

SLED PAD.

APPLICATION FILED FEB. 24, 1919.

Patented June 1, 1920.

Inventor

By

James Dickie
William S. Linton

Attorney.

UNITED STATES PATENT OFFICE.

JAMES DICKIE, OF SUMMERSIDE, PRINCE EDWARD ISLAND, CANADA.

SLED-PAD.

1,341,708.

Specification of Letters Patent.

Patented June 1, 1920.

Application filed February 24, 1919. Serial No. 278,975.

To all whom it may concern:

Be it known that I, JAMES DICKIE, a subject of the King of Great Britain, residing at Summerside, Prince Edward Island, Canada, have invented certain new and useful Improvements in Sled-Pads; and I do hereby declare that the following is a full, clear, and exact description of the invention, such as will enable others skilled in the art to 10 which it appertains to make and use the same.

The present invention relates to harness for draft animals and more particularly to a sled pad or saddle.

15 An object of the present invention is to provide a pad of this character which can be cheaply manufactured, thereby rendering the same commercially desirable, at the same time requiring less material than that of ordinary saddles and being much stronger and 20 durable.

A further object of the present invention is to provide a detachable connection for such sled pads whereby the girth strap and 25 belly band may be easily and readily connected thereto or detached therefrom should any part thereof become worn or broken.

With the above and other objects in view which will hereinafter appear as the 30 description continues, the invention consists of the novel features of construction, combination and formation of parts as will be hereinafter more fully described and particularly pointed out in the appended claims.

35 In the accompanying drawings has been shown a simple and preferred form of the invention, it being, however understood, that no limitation is necessarily made to the precise structural details herein exhibited, but 40 the right is hereby reserved to any changes, alterations or modifications to which recourse may be had that come within the scope of the claims without departing from the spirit of the invention or sacrificing the 45 efficiency of the same.

In the accompanying drawings:

Figure 1 is a perspective view of the sled pad embodying the present invention;

50 Fig. 2 is an enlarged detail section showing one form of the connection between the girth strap and belly band and the padtree;

Fig. 3 is a perspective view of the connecting member;

Fig. 4 is a sectional view similar to that of Fig. 2, but illustrating a slightly modified 55 form of the invention, and

Fig. 5 is a detail plan view.

Referring now more particularly to the accompanying drawings wherein like and corresponding parts are designated by similar reference characters throughout the several views.

The sled pad embodying the present invention comprises a saddle consisting of a padtree 1 which is preferably made of an 65 upper and lower strip of leather indicated by the numerals 2 and 3 respectively, which are connected together by means of the stitching 4. Secured to the lower face of the padtree are the pads 5. Adapted to be 70 connected to this padtree is a girth strap 6 which consists of two sections having their ends adjustably connected by means of the buckle 7 and also adapted to be connected to the padtree are the shaft bearing straps 8 75 provided with the shaft togs 9, and adjustably connected through the buckles 10 of the shaft bearing straps is a belly band 11. The ends 12 of the girth strap 6 are adapted to extend between the opposite ends of the 80 strips of leather 2 and 3, which form the padtree and these ends 12 are secured in place by means of the threaded ends 13 of the terrets 14 through which the driving rings may pass. The shaft bearing straps 85 8 are provided with the loops 15 which are also connected to the padtree and secured in place by means of the clips 16 and the terrets 14. The clips 16 are preferably made of a single piece of metal and which preferably consists of copper. One end 17 of these clips is adapted to be inserted within one of the openings 18 formed within the leather strip 2 and is adapted to rest between the strips 2 and 3. This clip is provided with a loop 19 in which is also adapted to rest one of the loops 15 and the opposite end 20 of each clip is provided with an opening 21 through which extends the threaded portion 13 of the terrets. 100

Secured to the under face of the leather strip 2 is a metallic plate 30 which is secured to this strip 2 by means of rivets 31 or similar fastening members. This reinforcing plate 30 is provided with an opening 32 105 adapted to register with the opening 18

within the strip 2, so as to reinforce this opening and prevent the clips from pulling loose and to avoid wear on the leather.

From the foregoing it is obvious that by 5 removing the turrets from the padtree the girth strap or shaft bearing straps may be readily released and should either of these straps become worn or broken new ones may be easily and readily substituted therefor; 10 without requiring the services of an expert saddle maker.

In Fig. 4 of the drawings I have illustrated a slightly modified form of the invention in which the ends 12 of the girth 15 strap extend up within the openings 18 of the saddletree and their extremities are stitched as at 22 to the strip 2 of the padtree and a loop 23 is formed so that the loops 15 of the shaft bearing straps may be connected 20 thereto. The turrets 14 may be screwed in place and will also provide means for better securing the end 22 of the girth strap to the padtree.

The pads 5 consist of an outer lining 25 preferably made of leather which is so formed that outer flanges are established and these outer flanges are connected by means of two rows of stitching as shown to the under face of the padtree 1 and a suitable 30 filler is retained in position by means of these outer linings. By making the pad lining in this particular manner the pad may be sewed to the padtree by means of an ordinary sewing machine, thereby greatly

reducing time and labor in assembling the 35 sled pad.

Having thus fully described my invention, what I claim as new and desire to secure by Letters Patent is:

1. In a device of the character described 40 comprising a padtree, a girth strap consisting of sections, the ends of said girth strap sections adapted to extend within said padtree and connected therewith, shaft bearing straps, plates arranged in said padtree, said 45 plates formed with openings, clips having one end disposed within said plate openings, and turrets adapted to pass through the opposite ends of said clips for detachably connecting the shaft bearing straps and clips 50 to the padtree.

2. A harness saddle comprising two rectangular pieces of leather stitched together, pads secured to the lower of said pieces, girth straps having their inner ends extending between said pieces, plates arranged between the saddle pieces, clips detachably secured at one end to said plates and at the opposite ends to said saddle, shaft bearing straps provided with loops adapted for engagement with the clip loops and turrets extending through said clips and girth straps for connecting the said elements to the said saddle.

In witness whereof I have hereunto set 65 my hand.

JAMES DICKIE.
